UNITED STATES PATENT OFFICE.

HAROLD H. STEVENS, OF LOS ANGELES, CALIFORNIA.

JAR COVER AND FASTENER.

SPECIFICATION forming part of Letters Patent No. 696,113, dated March 25, 1902.

Application filed April 2, 1901. Serial No. 54,043. (No model.)

To all whom it may concern:

Be it known that I, HAROLD H. STEVENS, a citizen of the United States, residing at Los Angeles, in the county of Los Angeles and 5 State of California, have invented new and useful Improvements in Jar Covers and Fasteners, of which the following is a specification.

My invention relates to fruit-jars, covers, 10 and fasteners, and its objects are to provide a jar of improved construction and improved means for insuring an absolutely air-tight closure thereof.

The invention consists in a jar of novel construction which avoids the contraction of the 15 mouth, thus facilitating filling and cleaning, in a cover of special form coöperating with the jar to afford a tight joint and a neat attractive appearance, and in improved means 20 for firmly clamping the cover in place upon the jar.

The characteristic features of the invention will be fully described hereinafter in connection with the accompanying drawings, which 25 form a part of this specification, and the points of novelty will be defined in the appended claim.

In the drawings, Figure 1 is a side elevation, partly broken away and partly in section, of a fruit-jar, cover, and fastener embodying the invention; and Fig. 2 is a top plan view of the same.

The reference-numeral 1 designates the body of the jar, which is cylindrical in form 35 and of the same internal diameter throughout its length, thus avoiding the usual internal annular shoulder at the mouth and facilitating filling, emptying, and cleaning.

2 designates an annular lip projecting from 40 the upper end of the jar and slightly beveled on its under surface, as clearly shown in Fig. 1, for a purpose hereinafter explained. From the upper surface of the lip 2 projects an annular flange 3, the upper surface of which is 45 formed with a continuous depression 4.

The cover 5 is slightly dished or hollowed out on its upper side, and from its under surface depends an annular shoulder 6, which fits snugly within the upper end of the jar.

The periphery of the cover rests flush with 50 the peripheral edge of the lip 2 of the jar, thus presenting a neat and compact appearance. I preferably also provide the under side of the cover 5, outside of the shoulder 6, with an annular bead 7, which registers with 55 the depression 4 in the lip and coacts therewith to firmly clamp a gasket 8. This gasket encompasses the outer side of the shoulder 6 and is applied thereto before the cover is placed in position upon the jar. 60

The cover-fastening consists of a clamp 9, having its ends 10 turned inward to engage below the beveled surface of the lip 2, which latter permits the hooked ends of the clamp to set close to the outer surface of the jar, as 65 shown, where strain will be more easily withstood. The clamp 9 is formed with a central internally-threaded bearing to receive a clamping-screw 11, formed at its upper end with a thumb-piece 12 and having riveted to 70 its lower end a spring preferably made from a single piece of metal and consisting of a central portion 13, through which the securing-rivet 14 extends, and four radially-projecting spring-arms 15. The thumb-piece 12 75 of the screw is perforated to receive a wire bail 16, which is adapted to straddle the clamp 9 after the screw has been turned to secure the cover, thus locking the screw against movement, or if the jar is used commercially the hole in the thumb-screw may receive a seal to insure purchasers of the 80 genuineness of the jar's contents. The flat sides of the screw may bear any suitable impress or advertising matter. 85

I preferably make my improved jar of heavy tough glass to permit special treatment of various fruits and vegetables after the jar is filled.

When the cover is clamped by means of 90 the screw, the spring-arms distribute the pressure equally, thus reducing to the minimum the liability of fracturing the jar or cover and at the same time affording the tension required to insure a tight joint. Any 95 loss of tension in the spring-arms is compensated for by turning the screw. The concavity of the upper side of the cover affords

a more direct resistance for the spring-arms than if the top of the cover were flat.

I claim—

The combination with a fruit-jar and its
5 cover, of cover-securing means comprising a
clamp spanning the cover and secured to the
jar; a thumb-screw extending through the
clamp and formed with an opening; and a

locking-bail extending through said opening
and adapted to straddle the clamp. ¹⁰

In testimony whereof I affix my signature
in presence of two witnesses.

HAROLD H. STEVENS.
